METHOD OF AND APPARATUS FOR INDUCTION HEATING OF SMALL AREAS

Otto M. Marquardt, Oakland Township, Oakland County, and Walter A. Majeska, Grosse Pointe, Mich., assignors, by mesne assignments, to The Ohio Crankshaft Company, Cleveland, Ohio, a corporation of Ohio

Application April 24, 1946, Serial No. 664,478

3 Claims. (Cl. 219—13)

1

This invention relates to induction heating, with particular application to the heating of small flat areas.

According to recognized methods of inductively heating small areas such as rod ends, a coil of any suitable electric conductor is constructed with a central axial opening made by the turns of the coil, and in this opening the bar, the end of which is to be heated, is inserted. On the application of electrical power to the coil heat arising from the alternating magnetic flux permeates the rod end and heats the same to a desired temperature whereupon the rod is quenched by appropriate means and a hardened end is secured which adapts the rod for tappet or other uses.

A deficiency arising from this method of bar heating is that by insertion of the rod end in the coil too large a mass of the rod is heated. In a tappet rod, for example, it is necessary only that the extreme end be heat treated. Within the opening of the coil it is impossible to avoid a substantial amount of heating for a relatively large distance from the rod end even though a single-turn coil is used.

It is an object of the present invention to provide a construction for an induction heating coil which permits heat treatment of a metal surface in a closely restricted region.

Another object of the invention is to provide a heating method which will insure substantial uniformity of heating across the area heated.

A related object is the securing of a uniform heating in a small area for a limited depth only.

An object also is to provide an inductive heating coil with means for securing at will any desired heat pattern across the face of a workpiece adjoining the heating coil of the heating apparatus.

Referring to the drawings:

Figure 1 is a plan view of the induction coil with the insulation plate broken away to show the core;

Figure 2 is a section along lines 2—2 of Figure 1 showing the heat pattern on the workpiece;

Figure 3 is a view of a coil provided with a circular core;

Figure 4 is a section along lines 4—4 of Figure 3 and showing also the heat pattern on a workpiece;

Figure 5 is a view of the conventional heating means for a rod end; and

Figure 6 is a sectional view along lines 6—6 of Figure 5 showing the heat pattern on the rod.

Prior art methods of developing high tempera-

tures in small areas, such as a tappet rod end, have followed the procedure shown in Figures 5 and 6 in which a single-turn induction coil 1 formed of the parallel terminal ends 2 and 3 and the circular enclosing coil turn 4 is adapted to receive a cylindrical rod end 5 for heating. The passage of current between the terminals 2 and 3 of the coil develops therein magnetic flux following the general pattern indicated by dashed lines 6 in Figure 6, these lines penetrating the permeable ferro-magnetic rod end and through hysteresis and eddy current developing a temperature therein exceeding the critical temperature for magnetic effects. The heat pattern is shown in Figure 6, and it is apparent that the depth of heating is substantial and in excess of that required for end heating, such as would be necessary in a tappet rod. As a result the energy absorbed by the unit is greatly in excess of that necessary, and wastage results.

The applicants in considering this problem of wastage and the desirability of limiting the heating effect to the zone immediately adjacent the end of the rod, succeeded in securing improved results by the arrangement shown in Figures 3 and 4. In the construction of these figures a U-shaped heating turn 10 is employed enclosing a heating chamber 11 in which a cylindrical lining 12 of insulation is placed enclosing a plurality of ferro-magnetic wire strands 13, such as iron. These strands are closely packed together and coated with insulating material so as to reduce or eliminate interstrand electrical conductivity. Appropriate work plates of dielectric substance may cover the substance of the coil and the ends of the core to support the workpiece, but in the particular form as shown this plate has been omitted. It is apparent from the heat pattern of Figure 4 that the magnetic flux penetrates the edge of the rod 29 with greater density and with a resultant higher heating effect so that after the heat treatment, by quenching, the hardened areas are at the edge of the end of the rod. This, while not affording a uniformly hardened region, is useful in such cases where edge hardness is paramount in need.

The form of disclosure of Figures 1 and 2 has been found to be particularly useful for securing a heat pattern of substantially uniform and reduced thickness. In this form of the construction a U-shaped coil turn 15 is employed having parallel terminal sections 16 and 17 with appropriate apertures 18 for fastening to electrical conductors. The inner bend or bight of the coil 55 is shaped as a Greek cross and lined with insu-

lation, as at 19, and within the insulation a plurality of ferro-magnetic wire strands 20, such as iron, each insulated, is closely packed to form the core 21. As shown in Figure 2, the ends of this core are flush with the plane of the coil sides, and overlying the ends and the adjoining section of the coil are dielectric plates 22 and 23. These plates serve to form a support for the end of the rod or any other workpiece which is to be heated and to maintain the wire strands in place within the coil turn.

The purpose of using a cruciform core is to cause a distribution of the magnetic flux with a greater concentration toward the center of the core than in the region approaching the circumference of the circle with a diameter equal to the maximum cross-sectional dimension of the core. In other words, a cylinder through the core having a diameter equal to the minimum diameter or cross-sectional dimension of the core from points 24 to 25 will have greater average flux concentration per unit area than the region between this cylinder and a cylinder whose diameter extends between points 26 and 27. Consequently, there will be a tendency for the magnetic flux to extend into the rod tip 30 a greater distance toward the center than would occur if this variation in the core density did not exist. The heat pattern of Figure 4 indicates the result where there is a uniform distribution of the core material throughout the large diameter thereof. Accordingly, by varying the average density of the core structure from axis to major circumference; i. e., in any circumferential zone, the flux pattern may be modified and the heat pattern consequently changed as desired either to secure a uniform heating or variations from uniformity to edge heating, as shown in Figure 2.

For illustrative purposes certain structure has been specified which is not necessary for the objects of the invention. For example, insulation wire strands have been indicated as the core substance. Obviously other core materials may be used, such as powdered iron or solid magnetic metal. Also, a cruciform core has been indicated as desirable. To secure modified heating effects the core may be star shaped or follow any other polygonal shape, as desired. Other variations of the invention may be made and hence no limitation is implied by the specific disclosure other than that may be required by the claims as hereto appended.

What is claimed is:

1. A method of rapidly heating an area of a generally flat metal surface with a high-frequency magnetic flux of a frequency such that it does not substantially penetrate below the surface of the metal comprising the steps of generating an alternating magnetic flux field entirely on one side of said surface and of such a fre-

quency that it does not substantially penetrate below said surface, distorting said flux field to provide for any complete circumferential zone measured from the center a maximum average density greatest at and adjacent the center and decreasing outwardly toward the outer limitations of said field and causing said distorted flux field to flow into said metal surface.

2. Electrical induction - heating apparatus adapted to heat metal surfaces of a lesser area than the overall area of the apparatus comprising a coil including one or more turns of a conductive material adapted to have a high-frequency alternating current circulated therethrough, said coil defining a central opening and having a work side at one side of the opening adapted to be positioned in proximity to the surface to be heated, said opening having a magnetic core disposed therein with both ends of said core positioned on one side of a plane passing through the plane of said surface, said core having an average magnetic density for any complete circumferential zone which continuously decreases at least from a point spaced from its central axis to the outer edge thereof.

3. Electrical induction - heating apparatus adapted to heat metal surfaces of a lesser area than the overall area of the apparatus comprising a coil including one or more turns of an electrically conductive member defining a central opening, said coil adapted to be positioned in proximity to the surface to be heated with one end of said opening facing said surface, a magnetic core member in said opening, said core member having a central portion and a plurality of projections extending generally radially from said portion, said projections forming a core of decreasing average magnetic density in any complete circumferential zone outwardly from said portion.
